UNITED STATES PATENT OFFICE

WILLIAM H. GERTH, OF NEW YORK, N. Y., ASSIGNOR TO ONEIDA COMMUNITY LIMITED, OF ONEIDA, NEW YORK, A CORPORATION OF NEW YORK

DESIGN FOR A DISH OR SIMILAR ARTICLE

Application filed September 15, 1931. Serial No. 41,117. Term of patent 14 years.

To all whom it may concern:

Be it known that I, WILLIAM H. GERTH, a citizen of the United States of America, residing at 307 East 44th Street, New York city, New York, have invented a new, original, and ornamental Design for a Dish or Similar article, fully described and represented in the following specification and the accompanying drawing forming a part of the same, said drawing being a plan view of a dish showing my new design, the essential feature of which is the central ornamental matter in the bowl of the dish or similar article and the circular ornamental matter contiguous to the bowl and which is continuous throughout the rim although shown for only a portion thereof.

I claim

The ornamental design for a dish or similar articles as shown and described.

In testimony whereof I have hereunto set my hand.

WILLIAM H. GERTH.
